Paula S. Gooding.

UNITED STATES PATENT OFFICE.

LUTHER D. HASKELL, OF ESSEX, MASSACHUSETTS.

WINDOW.

1,196,860.

Specification of Letters Patent.

Patented Sept. 5, 1916.

Application filed June 8, 1915. Serial No. 32,825.

To all whom it may concern:

Be it known that I, LUTHER D. HASKELL, a citizen of the United States, residing at Essex, in the county of Essex and State of Massachusetts, have invented new and useful Improvements in Windows, of which the following is a specification.

This invention relates to improvements in windows.

10 The object of the invention is to provide an inexpensive neat and tight window, especially constructed to facilitate the removal and replacing of the sashes of said window, and at the same time practically eliminate 15 the possibility of the free movement of the sashes thereof being hampered by any swelling of portions of the sashes thereof.

20 The invention consists in the combination and arrangement of parts whereby the above objects and certain other objects hereinafter appearing may be attained as set forth in the following specification and particularly pointed out in the claims.

25 Referring to the drawings: Figure 1 is a vertical section through one side of a window frame and sash embodying my invention. Fig. 2 is a section taken on the line 2—2 of Fig. 1. Fig. 3 is a section taken on the line 3—3 of Fig. 1. Fig. 4 is a section 30 similar to Fig. 3 showing another method of securing the guiding strip to said sash.

Like numerals refer to like parts throughout the several views of the drawings.

In the drawings, 99 represents one of the 35 side stiles of a window sash 100, and 101 is a pulley piece of a window frame 90 against which the sash 100 is adapted to reciprocate. A weather or guide strip is provided for the purpose of guiding the sash within said 40 frame, and consists preferably of a strip sheet material 102 preferably formed of metal and arranged within a slot 103 formed in the edge 92 of said sash, which abuts against the pulley piece 101 of the window frame 45 said strip being substantially equal in length to the side stile of the sash containing the slot 103. Said slot extends from the top substantially to the bottom of said side stile 99 and is open at its upper and lower ends 50 to permit said strip 102 to be inserted either from the upper or from the lower end of said slot.

Pins 104, 104 extend transversely of the 55 strip 102 through portions of the side stile 99 and prevent the longitudinal displacement of said strip 102 after it has once been

placed and secured in position within the slot 103. The strip 102 protrudes from the slot 103 toward the pulley piece 101 and the protruding portion thereof projects into a slot 105 arranged longitudinally of said pulley piece and substantially in alinement with the slot 103 of the sash 100. Springs 106 are secured within the slots 105 in contact with one face of said strip 102 for the purpose of yieldingly retaining said strip in contact with the opposite side of said slot from that to which said springs are secured.

60 Fig. 4 shows a weather or guide strip in all respects similar to the one hereinbefore described with the exception that the weather strip 102 is secured to the side stile by a screw or screws 107 instead of by means of pins 104. To remove the guide strips 102 so as to permit the sashes to be removed from the window frames the pins 104 or the screws 107 are first withdrawn thereby releasing said strips and permitting the same to be withdrawn upwardly or downwardly from the slot 103 according to the position of the 65 sash within the frame. After said strips have been withdrawn as described the sashes may be removed from the casing without resistance. The present drawings illustrate 70 but one side of a window frame and sash, the opposite side of said sash and frame is however but a duplication of the sides shown in the drawings, therefore further illustration thereof will not be necessary.

75 Having thus described my invention what I claim and desire by Letters Patent to secure is:

1. A window having, in combination, a sash provided with a slot extending longitudinally of the side thereof, a frame within 80 which said sash is adapted to slide, said frame having a slot coinciding with the slot in said sash, a strip of sheet material detachably secured to said sash within said slot and slidable within the slot in said frame, 85 means constructed and arranged to detachably secure said strip to said sash and means for retaining said strip in yielding contact with one side of the slot in said frame.

90 2. A window having, in combination, a sash provided with a slot extending longitudinally of the side thereof, a frame within 95 which said sash is adapted to slide, said frame having a slot coinciding with the slot in said sash, a strip of sheet material detachably secured to said sash within said slot and slidable within the slot in said frame,

means constructed and arranged to detachably secure said strip to said sash, and a plurality of springs arranged within the slot in said frame adapted to engage one face of 5 said strip and retain said strip in yielding engagement with said frame.

3. A window having, in combination, a sash provided with a slot extending longitudinally of the side thereof, a frame within 10 which said sash is adapted to slide, said frame having a slot coinciding with the slot in said sash, a strip of sheet material detachably secured to said sash within said slot and slidable within the slot in said

frame, means constructed and arranged to 15 detachably secure said strip to said sash, and a plurality of flat springs arranged within the slot in said frame adapted to engage one face of said strip and retain said strip in yielding engagement with one side 20 of the frame forming said slot.

In testimony whereof I have hereunto set my hand in presence of two subscribing witnesses.

LUTHER D. HASKELL.

Witnesses:

LEVI L. BARNES,
ALLEN DOYLE.
